Jas. Blackman & Chas. Skidmore

Design for Combs

Patented Feb. 17. 1852.

James Blackman and Charles Skidmore of Newtown Fairfield Co Conn Letters Patent No 446 Dated Feb 17th 1852

The schedule referred to in these Letters Patent, and making part of the same

To all whom it may concern,

Be it Known

That we James Blackman and Charles Skidmore, of Newtown in the county of Fairfield, and State of Connecticut, have invented or produced a new and ornamental design for the upper part of the backs of ladies hair combs and we do hereby declare that the following is a full clear and exact description of the same reference being had to the annexed drawings, making a part of this specification in which

Fig 1 is a back view of a lady's hair comb showing the ringlets or curls which, constitute the design, on the upper part of the back of the comb.

Fig 2 is a side view of ditto Similar letters of reference indicate corresponding parts in each of the two figures,

The design, consists of a series of Ringlets or, curls formed on the upper part of the back of the Comb.

A represents the design, composed or formed of the ringlets or,curls (a) the ringlets or curls are bent over, and rest on the upper part of the back of the comb above the teeth (b) see both figures, the ringlets or curls are not in a vertical position but are somewhat inclined, those on one side of the centre of the comb inclining in a reverse direction from those on the other side. See fig 1 the series of ringlets or curls form a curve on the upper part of the comb precisely as shown in fig 1

What I claim as new and desire to secure by Letter Patent is

The design A composed or formed of a series of ringlets or curls (a), said ringlets or curls forming a curve and placed on the upper part of the back of the comb the ringlets or curls being in an inclined position those on one side of the centre of the comb inclining in direction reverse from those on the other side substantially, as herein shown and described.
